UNITED STATES PATENT OFFICE.

CHARLES J. AHRENFELDT, OF NEW YORK, N. Y.

DESIGN FOR A CUP.

SPECIFICATION forming part of Design No. 29,122, dated August 2, 1898.

Application filed February 9, 1898. Serial No. 669,723. Term of patent 7 years.

To all whom it may concern:

Be it known that I, CHARLES J. AHRENFELDT, a citizen of the United States, residing at the city of New York, in the county and State of New York, have invented and produced a new and original Design for a Cup, of which the following is a specification.

My design consists of a cup having the shape and ornamentation hereinafter described, reference being had herein to the accompanying drawings, forming a part hereof, in which like letters of reference refer to like parts in each figure.

Figure 1 is a side view of a cup embodying my design. Fig. 2 is a vertical cross-section of the same. Fig. 3 is a bottom view of the same.

The base of the cup A' is provided with a series of indentations B, leading to lines of depression B', thus giving the same a multi-foil form. These lines of depression B' extend upward on the surface of the cup, so that the same at its medial portions will also present a multi-foil shape in horizontal section. The lines of depression gradually merge as they approach the rim of the cup, which is smooth and circular in form. Between the base and the rim of the cup is a bulged portion A², upon which is the circumferential

ornamentation, consisting of a band of latticed work C, the lines of which are provided with small circles c at the points of intersection, bordered on either side by a series of parallel scrolls D, with volute terminals d and fin-like projections d' on the inner side near the terminals, and directly above each upper bordering scroll a cruciate leaf ornament E, with two foliate ornaments e on either side and a scroll having a volute terminal e'.

The handle of the cup consists of two projecting curved portions F, the lower one being provided with latticed work f similar to that on the body of the cup and a scroll-like border f', the upper one being provided with a series of small circles bordered by a scroll, 45 the two portions F supporting a volute scroll G, forming the extreme outward portion of the handle.

What I claim is—

The design for a cup herein shown and described.

In witness whereof I have hereto affixed my signature in the presence of two witnesses.

CHARLES J. AHRENFELDT.
